CLAIM

The ornamental design for a tape cartridge holder, as shown and described.

DESCRIPTION

FIG. 1 is a perspective view of a tape cartridge holder showing my new design;

FIG. 2 is a front elevational view thereof;

FIG. 3 is a rear elevational view thereof;

FIG. 4 is a top plan view thereof;

FIG. 5 is a bottom plan view thereof; and

FIG. 6 is a right side elevational view thereof, the left side being a mirror image of that shown.

FIG. 1

FIG. 4

FIG. 2

FIG.3

FIG.5

FIG. 6
